REGULATING DEVICE

Johann Heinrich, Berlin-Tegel, Germany, assignor, by mesne assignments, to Maschinen- und Metallwaren-Handelsgesellschaft m. b. H., Berlin, Germany, a limited-liability company of Germany

Application June 29, 1938, Serial No. 216,489
In Germany February 13, 1937

3 Claims. (Cl. 62—3)

This invention relates to a regulating device for refrigeration plants and refers more particularly to means for automatically regulating the amount of liquid in evaporators of refrigeration plants.

An object of the present invention is the provision of an automatic regulating device of this type which is solid and dependable in operation and which will not jam or get out of commission due to the pressure of the cooling medium.

Another object is the provision of an automatic regulating device for refrigeration plants, the movable parts of which can easily overcome the friction resulting from the pressure of the cooling medium.

Other objects of the present invention will be apparent in the course of the following specification.

The objects of the present invention may be realized through the provision of a flow valve which is included in the conduit supplying the liquid cooling medium to the evaporator, and which is operated by the compressed gaseous cooling medium depending upon the position of a float which indicates the level of the liquid cooling medium in the evaporator. The flow of the compressed gaseous cooling medium to the valve is regulated by a pivot which is connected to the float, and which provides for the removal of the compressed gaseous cooling medium from the valve and the closing of the latter when the liquid cooling medium in the evaporator has reached a desired level.

The invention will appear more clearly from the following detailed description when taken in connection with the accompanying drawings, showing by way of example a preferred embodiment of the inventive idea.

In the drawings:

Figure 1 illustrates diagrammatically, partly in section, a regulating device constructed in accordance with the principles of the present invention;

Figure 2 is an enlarged detail view in section, of the float container;

Figure 3 is a section along the line 3—3 of Figure 2 on a larger scale; and

Figure 4 is a section along the line 4—4 of Figure 2.

Figure 1 shows an evaporator 5 which may be filled with the liquid cooling medium and which carries a container 6. The interior of the container 6 is connected with that of the evaporator 5, so that the level of the liquid in the container 6 depends upon that of the evaporator

5. The container 6 is connected by means of a pipe 7 with a compressor 8, which is illustrated diagrammatically in the drawings.

A pipe 9 is connected to the lower portion of the container 6 and leads to another container 10 which serves as a casing for the float 11. Due to the provision of the pipe 9, the level of the liquid cooling medium in the container 10 depends upon that in the container 6 and the evaporator 5.

The container 10 is illustrated in greater detail in Figures 2 and 3 of the drawings. This container comprises a casing 12, which encloses the float 11 and which is connected by the bolts 13 to the portion 14 serving as a support or bearing for the steering pivot or pin 15. The end 18 of the pivot 15 is rotatably mounted in a support 19, which is connected by the bolts 20 to the portion 14 of the container 10. The arm 17 of the float 10 is provided with a rectangular opening into which the rectangular portion 16 of the pivot 15 is fitted, so that when the float 11 moves up and down following the level of the liquid in the container 10, the pivot 15 will rotate within its support 14.

The pivot 15 is provided with a groove 21 which extends in the direction of the pivotal axis. The pivot 15 is also provided with a bore-hole 22 extending through the pivot at right angles to its axis and communicating with the passage or groove 23 which leads to the chambers 24 and 25 formed within the portions 14 and 12 of the container 10.

The portion 14 of the container 10 is provided with two openings 26 and 27, which are so located that they are interconnected by the groove 21 when the pivot 15 is turned by the lowering of the float 11, caused by the dropping of the level of the liquid within the container 10.

The opening 26 is in communication with a pipe 28 which leads to the valve 38. This valve comprises a cylinder 29 and a piston 30 which is reciprocable within the cylinder 29 and which is engaged by a spring 31. The piston 30 is connected by a piston rod 32 with a valve body 33, adopted to close the passage 34, which interconnects two passages 35 and 36 provided in the valve casing 37. The spring 31 tends to maintain the valve body 33 in the closed position.

The device 38 is a flow valve which is included in the conduit 39 connecting the condenser 40 with the container 6.

The opening 27 provided in the portion 14 of the casing 10 is connected to a pipe or con-

duit 41 which is in communication with the compressor 8.

The operation of the device is as follows:

When there is a sufficient amount of the liquid cooling medium in the evaporator 5, the level of the liquid in the containers 6 and 10 is substantially high, so that the rod 17 of the float 11 which follows the level of the liquid, will extend substantially horizontally. In that position, the groove 21 of the pivot 15 is situated below the openings 26 and 27, so that there is no communication between these openings or between the pipes 41 and 28.

When the amount of the liquid in the evaporator 5 is diminished, the float 11 will gradually move downwards, thereby turning the rod 17 and the pivot 15. Due to this turning of the pivot 15, the groove 21 will move gradually upwards and at a time when the level of the liquid is at its lowest, it is situated opposite the openings 26 and 27, so that it interconnects these openings.

Then the compressed gaseous cooling medium in the compressor 8 will flow through the pipe 41 into the opening 27 provided in the portion 14 of the casing 10. Thence the compressed gas will flow through the groove 21 and the opening 26 reaching the pipe 28 which is connected with the opening 26. The compressed cooling medium will flow through the pipe 28 into the interior of the cylinder 29 of the valve 38 and will exert a pressure upon the piston 30 moving this piston downward against the action of the spring 31.

Since the piston 30 is connected by the piston rod 32 with the valve body 33, this movement of the piston 30 and of the valve body 33 connected therewith will free the passage 34 so that a connection will be established between the passages 35 and 36 provided in the valve casing 37. Since the passages 35 and 36 constitute a part of the conduit 39 connecting the condenser 40 with the container 6, the movement of the valve body 33 will establish a connection between the condenser 40 and the evaporator 5, with the result that the liquid cooling medium will flow from the condenser 40 to the evaporator 5.

Thus the level of the liquid in the evaporator 5 will be raised so that the float 11 will gradually move upward. At the same time, the groove 21 will move downwards due to the rotation of the pivot 15 until the connection between the openings 26 and 27 is interrupted again.

The compressed gaseous cooling medium situated in the cylinder 29 will leave the cylinder through the pipe 28, the opening 26 in the casing 10, and the passages 22 and 23 formed in the pivot 10. The valve 38 will be closed again and the connection between the evaporator 5 and the condenser 40 will be interrupted.

The cooling medium evaporated or situated in the chambers 24 and 25 of the container 10 may leave these chambers through a pipe 42 which connects the container 10 with the upper portion of the container 6.

The valve 38 is preferably provided with a spindle 43 which is used for manually interrupting the connection between the condenser 40 and the container 6 in case of repairs.

The regulation of the lever of the liquid in the evaporator is carried out in a simple and effective manner by means of the described construction and the size of the steering pivot may be comparatively small due to the fact that no large passages are required for the compressed gas, so that no difficulties are likely to arise in the operation.

It is apparent that the specific illustration shown above has been given by way of illustration and not by way of limitation, and that the structures above described are subject to wide variation and modification without departing from the scope or intent of the invention, all of which variations and modifications are to be included within the scope of the present invention.

10. What is claimed is:

1. In cooling plants, in combination with an evaporator, a compressor connected with said evaporator, and a condenser; a conduit for supplying the liquid cooling medium from said condenser to said evaporator, said conduit including a flow valve, a casing connected with said evaporator, a float within said casing, a steering pivot operatively connected with said float and supported by said casing, said steering pivot having

15 a groove formed therein for interconnecting two openings formed in said casing, a conduit providing a communication between one of said two openings and the interior of said compressor, means actuating said valve, and another conduit providing a communication between the other one of said openings and the valve-actuating means.

2. In refrigeration plants, in combination, an evaporator, a compressor connected with said evaporator, a conduit for supplying the liquid cooling medium to said evaporator and comprising a flow valve, a float actuated by the level of the liquid in the evaporator, a steering pivot firmly connected with said float, said pivot having a groove formed therein, a casing connected with

20 said evaporator and carrying said pivot, said casing having two openings formed therein, said openings being interconnected by said groove in a predetermined position of said float, means connecting one of said openings with said compressor to supply compressed gaseous cooling medium from said compressor to that opening, means actuating said valve, and means providing a communication between the other one of said openings and the valve-actuating means to cause said

25 compressed gaseous cooling medium to operate said valve-actuating means in said position of the float.

3. In refrigeration plants, in combination, an evaporator, a compressor connected with said evaporator, a conduit for supplying the liquid cooling medium to said evaporator and comprising a flow valve, a float actuated by the level of the liquid in the evaporator, a steering pivot firmly connected with said float, said pivot having a groove formed therein, a casing connected with said evaporator and carrying said pivot, said casing having two openings formed therein, said openings being interconnected by said groove in a predetermined position of said float, means connecting one of said openings with said compressor to supply compressed gaseous cooling medium from said compressor to that opening, means actuating said valve, and means providing a communication between the other one of said openings and the valve-actuating means to cause said

30 compressed gaseous cooling medium to operate said valve-actuating means in said position of the float.

4. In refrigeration plants, in combination, an evaporator, a compressor connected with said evaporator, a conduit for supplying the liquid cooling medium to said evaporator and comprising a flow valve, a float actuated by the level of the liquid in the evaporator, a steering pivot firmly connected with said float, said pivot having a groove formed therein, a casing connected with said evaporator and carrying said pivot, said casing having two openings formed therein, said openings being interconnected by said groove in a predetermined position of said float, means connecting one of said openings with said compressor to supply compressed gaseous cooling medium from said compressor to that opening, means actuating said valve, and means providing a communication between the other one of said openings and the valve-actuating means to cause said

35 compressed gaseous cooling medium to operate said valve-actuating means in said position of the float.

5. In refrigeration plants, in combination, an evaporator, a compressor connected with said evaporator, a conduit for supplying the liquid cooling medium to said evaporator and comprising a flow valve, a float actuated by the level of the liquid in the evaporator, a steering pivot firmly connected with said float, said pivot having a groove formed therein, a casing connected with said evaporator and carrying said pivot, said casing having two openings formed therein, said openings being interconnected by said groove in a predetermined position of said float, means connecting one of said openings with said compressor to supply compressed gaseous cooling medium from said compressor to that opening, means actuating said valve, and means providing a communication between the other one of said openings and the valve-actuating means to cause said

40 compressed gaseous cooling medium to operate said valve-actuating means in said position of the float.
